Crane & Miller, atty.

UNITED STATES PATENT OFFICE.

AARON VREELAND, OF CEDAR GROVE, NEW JERSEY.

GAS-BURNER.

SPECIFICATION forming part of Letters Patent No. 326,358, dated September 15, 1885.

Application filed January 8, 1885. (No model.)

To all whom it may concern:

Be it known that I, AARON VREELAND, a citizen of the United States, residing in Cedar Grove, Essex county, New Jersey, have invented certain new and useful Improvements 5 in Gas-Burners, fully described and represented in the following specification and the accompanying drawings, forming a part of the same.

10 This invention relates to novel means of improving the draft within a gas-burner chimney, and is intended to alter the shape of the flame from a bat-wing, fan-tail, or other burner which produces a flat flame, in 15 such manner as to use the same within a vertical chimney, like a circular Argand burner, and thereby increases the degree of illumination secured by the combustion of a certain amount of gas in such a burner; and it consists 20 in the combination, with a gas-burner adapted to form a flat flame, of a vertical chimney, a base partly closing the bottom of the same, pillars extending from the base within the chimney and above the burner and 25 diaphragm movably supported upon the pillars, and provided with aperture for the passage of the flame.

30 In the drawings annexed, Figure 1 is a vertical section of the chimney, burner, and diaphragm. Fig. 2 is a plan of the chimney and the support for the same. Fig. 3 is a plan of the diaphragm. Fig. 4 is a plan of a brace, I, which may be applied to the pillars e to stiffen them, if required, the brace being shown 35 only in dotted lines in Fig. 1; and Fig. 5 shows a modified form of chimney-support.

40 A is a burner represented as attached to a pipe, B. C is a support or base fixed at the bottom of the burner to carry the chimney D, and provided with upright pillars e, to carry the diaphragm f within the chimney above the burner.

45 Four of the pillars are shown; and the diaphragm is represented as formed of thin sheet metal, with an oblong aperture, J, in the center for the passage of the contracted flame, and perforated with four holes to slip over the pillars, and having bent tongues g, formed by punching, at the sides of said holes in the 50 diaphragm, to bear elastically against the side of each pillar, and thus hold the diaphragm in its adjusted position.

In Fig. 1 the diaphragm is shown adjusted about one-half of an inch above the burner, and its effect is displayed in the contracted 55 and parallel form of the flame l above the diaphragm. The pillars extend sufficiently above the top of the burner to permit the sliding of the diaphragm up and down within the necessary limits to secure the best draft 60 upon the flame, and consequently the best combustion and illumination.

The diaphragm is adjusted by removing the chimney and sliding the diaphragm upon the pillars e to the desired position, and may 65 thus be adjusted to suit the pressure of the gas and the degree of light required.

The base C is shown in Fig. 2 as perforated with small holes h, to produce a restricted current of air to the interior of the chimney, 70 as in Argand burners; and a rotating and partially-perforated disk may be attached to the lower side of the base, if desired, and operated to cut off the supply of air through certain of the holes h when a very small 75 amount of gas is to be consumed; but a plain cross-bar—such as shown in Fig. 5—may be used as a base, if preferred. Four pins, k, are shown projected upward from the base to hold the chimney concentric with the burner; 80 but a flanged shoulder and vertical springs may be formed upon the base, as in Argand burners; or any other means to hold the chimney may be employed, as the same is immaterial to my invention. The brace I is 85 devised merely to stiffen the pillars, if it be desired to make them very slender, as it is requisite that they should hold the diaphragm centrally within the chimney, which it is not intended to touch, although fitted nearly to 90 its interior diameter to prevent any passage of the air-draft or flame at such point.

95 My invention thus affords a very cheap substitute for the circular Argand burner generally used with a vertical chimney.

Having thus fully set forth the nature and object of my invention, what I claim herein is—

1. The combination, with a gas-burner adapted to form a flat flame, of a vertical 100 chimney, a base partly closing the bottom of the same, pillars extending from the base within the chimney and above the burner, and a diaphragm movably supported upon

the pillars and provided with the aperture J for the passage of the flame, as and for the purpose set forth.

2. The combination, with a gas-burner
5 adapted to form a flat flame, of a vertical
chimney, a base partly closing the bottom of
the same, pillars extending from the base
within the chimney and above the burner,
and diaphragm constructed with holes, and
10 bent tongues g to press the pillars elastically,

and provided with the aperture J for the
passage of the flame, as and for the purpose
set forth.

In testimony whereof I have hereunto set
my hand in the presence of two subscribing 15
witnesses.

AARON VREELAND.
